UNITED STATES PATENT OFFICE.

HERBERT KNIGHT, OF BROCKLEY, ENGLAND, ASSIGNOR TO MALCOLM KING, OF ST. JOHN'S WOOD, MIDDLESEX, ENGLAND.

CARBURETER AND VAPORIZER.

1,344,698.

Specification of Letters Patent. Patented June 29, 1920.

Application filed May 1, 1918. Serial No. 231,873.

To all whom it may concern:

Be it known that I, HERBERT KNIGHT, a subject of the King of Great Britain, residing at 7 Montague avenue, Brockley, in 5 the county of Kent, England, have invented certain new and useful Improvements in and Connected with Carbureters and Vaporizers, of which the following is a specification.

10 This invention comprises improvements in and connected with carbureters and vaporizers, and has for its object to provide apparatus of this kind which is suitable for use with lower grade fuels or heavy hydrocarbons, such as paraffin, or with mixtures of liquid fuels such as are used in substitution of petrol. In the vaporization of these fuels, waste heat, such as that of the exhaust gases of combustion, has been utilized, 15 and the present improvements aim at obtaining a better and more efficient distribution of the heat so that the combustible mixture is heated and the liquid particles vaporized in a thoroughly uniform and satisfactory manner.

The type of apparatus, to which the invention refers, comprises a heat-exchange device for externally and internally heating the induction pipe or combustible mixture 20 supply pipe or a chamber mounted on or forming part of the induction pipe, and means for baffling or deflecting the heating medium for the purpose of rendering its distribution more uniform. In order to effectually heat the stream of combustible mixture, internal means are provided for withdrawing a portion of the exhaust gases from the chamber and circulating them through the induction pipe, an induced current device being fitted on an outlet pipe leading from the chamber to the atmosphere.

The invention will be hereinafter described with reference to the accompanying drawings and specifically pointed out in the claims.

In the drawings—

Figure 1 is a part sectional elevation of a vaporizer constructed according to this 50 invention,

Fig. 2 is a plan and

Fig. 3 is a vertical section on the line III III of Fig. 1.

Fig. 4 is a modified form of elbow and 55 Fig. 5 is an end elevation of same.

In one practical construction according to the present invention and as illustrated in Figs. 1, 2 and 3, the chamber *a* consists of an outer casing of, say, sheet iron lined with asbestos *b* and an inner casing or lining 60 of copper *c*. The casing is oblong in plan and, in end elevation, has vertical side walls *a*¹ and a curved roof or top *a*². This chamber *a* is suitably bolted down on the top of the carbureter *d* and one side wall is removable or fitted with a removable cover or door *e* for inspection purposes. The floor *a*³ and ends walls *a*⁴ *a*⁴ of the chamber may be of brass and on the floor *a*³ is bolted down the flanged end *f* of the stem of a 65 T-shaped copper pipe *g* of suitable dimensions for the passage of the combustible mixture. The hole in the floor *a*³, over which the pipe end *f* is fixed, is arranged to come over the delivery aperture of the carbureter *d* when the chamber is fixed in position. The ends of the horizontal arms of the T-shaped pipe *g* are secured tightly in holes in suitable thickened portions or bosses on the end walls *a*⁴ and on the exterior 70 surfaces of these end walls are secured elbow connections *h* and *h*¹ to which the induction pipe or pipes leading to the engine cylinders are connected. The exhaust pipe *i* admitting gases of combustion to the 75 chamber *a* is, preferably, connected to the rear wall near the top and mid-way between the ends, or in any other suitable position, and opposite the exhaust admission *i* and extending over the middle portion 80 of the horizontal part of the T-shaped induction pipe *g*, is a baffle *k* which is suitably curved to concentricity with the induction pipe *g*. This baffle plate *k* may be of copper and suitably extends around the pipe to 85 the extent of about 180° but the lower part *k*¹ of the plate *k* at the rear is flat and hangs vertically so as to direct part of the baffled gases downward. The baffle plate *k* is advantageously supported upon the induction 90 pipe *g* by means of fins or webs *l* which are secured radially, and so as to run longitudinally of the horizontal arms of the T-shaped pipe *g*. These fins or webs *l* may extend over almost the whole length of the 95 said arms in order to increase the heat-exchange capacity of the device, and while they may be brazed to the pipe *g*, their fixing may be strengthened by securing them to angles or webs *l*¹ running longitudinally 100 105 110

- of the pipe g and carried by rings m clamped around the pipe g near to the ends of the horizontal arms of the pipe g by means of bolts and nuts m^1 .
- 5 Outlets for the exhaust gases are preferably provided near the two ends of the chamber, and the outlet pipe n at one end is advantageously formed as a nozzle n^2 surrounded by a small annular chamber o .
- 10 A tube p is connected to the outlet pipe n^1 at the other end, and this tube p is carried through the horizontal portion of the T-shaped induction pipe g and then connected with a pipe q which leads into the small chamber o surrounding the nozzle n^2 . The tube p may be straight, wavy or spiral or of other sinuous formation and may be fitted with gills, wires or other heat-exchange devices. The small pipes n^1 q connecting respective ends of the tube p with the heat exchange chamber a and with the small chamber o surrounding the nozzle n^2 may be permanently connected with bosses on the under sides of the elbows h and h^1 aforesaid, and the ends of the tube p may be connected with nipples or hollow plugs r r^1 screwed down on to faced recesses on the interior of these bossed portions. As previously stated, more than one tube p may be arranged within the induction pipe g , if desired.
- 15 As shown in Figs 4 and 5 the elbows such as h^2 may be made taper so as to permit of using a chamber of larger dimensions or diameter and bolting the flanges of the said elbows to the ordinary bosses on the engine.
- 20 Although the particular construction of 85 vaporizer illustrated is applicable for use with a carburetor in which the fuel is fed under pressure, it is obvious that the invention is also applicable in case of the fuel being fed by gravity.
- 25 It will therefore be seen that the apparatus comprises a very large area of uniformly heated surfaces for contact with the combustible mixture, so that the latter becomes thoroughly and efficiently vaporized 95 before entering the engine cylinders. In practice, the engine may be started with petrol and may run for a few minutes on this or other suitable light fuel, after which paraffin or other cheaper or heavy fuel may 100 be supplied, as will be readily understood.
- 30 One of the advantages of the improved apparatus is that it is possible to fit it to existing engines with little trouble or structural alteration, as it may be merely substituted for the ordinary induction manifold pipe.

35 In operation, the hot gases of combustion entering the chamber a are delivered on to the baffle k and are distributed in all directions into the chamber, some passing over the curved top of the baffle k to the front of the chamber, and some passing downward at the rear and beneath the horizontal arms of the induction pipe g . In this 40 way the hot gases are disseminated throughout the chamber and, in addition, the heat taken up by the baffle k and by the fins or webs l is uniformly conducted over a large portion of the surface of the induction 45 pipe g .

An aperture is made preferably in the front of the stem portion of the T-shaped pipe g and a small valve casing s is tightly secured in this aperture. A ball valve t , 50 or other suitable valve, is pressed by a spring u against a seating s^1 in the valve casing s in the direction for preventing admission of the exhaust gases into the induction pipe g . On the front wall or in 55 the cover e of the chamber and opposite the admission aperture of the valve casing s is fitted a sleeve or stuffing box v in which a rod w is mounted and suitably guided. A spring w^1 inserted between the front wall 60 and a collar w^2 on the rod w constantly presses the rod w outward away from the valve t . The rod w may be forced inward against the valve t by means of a bell-crank lever x operated, for example, by a 65 Bowden wire y (Fig. 2) from the driver's

seat. When it is desired, therefore, to impart additional heat to the mixture, a pull on the wire y effects an opening of the valve t which thereupon admits a small quantity of hot gases from the chamber a into the 70 induction pipe g , and such hot gases mingle with the combustible mixture. Upon releasing the wire y the spring u immediately closes the valve t and shuts off the admission of the hot gases. A copper gauze or 75 other suitable baffle s^2 may be fitted in the valve casing s so as to insure the impossibility of any flame reaching the interior of the induction pipe g .

As shown in Figs 4 and 5 the elbows such 80 as h^2 may be made taper so as to permit of using a chamber of larger dimensions or diameter and bolting the flanges of the said elbows to the ordinary bosses on the engine.

Although the particular construction of 85 vaporizer illustrated is applicable for use with a carburetor in which the fuel is fed under pressure, it is obvious that the invention is also applicable in case of the fuel being fed by gravity.

It will therefore be seen that the apparatus comprises a very large area of uniformly heated surfaces for contact with the combustible mixture, so that the latter becomes thoroughly and efficiently vaporized 95 before entering the engine cylinders. In practice, the engine may be started with petrol and may run for a few minutes on this or other suitable light fuel, after which paraffin or other cheaper or heavy fuel may 100 be supplied, as will be readily understood.

One of the advantages of the improved apparatus is that it is possible to fit it to existing engines with little trouble or structural alteration, as it may be merely substituted for the ordinary induction manifold pipe.

Although in the example described, two elbows are said to be fitted, these being for the supply to two engines or two sets of 110 cylinders, it is obvious that this detail of the apparatus may be varied to suit the particular requirements of any engine to which the device is to be fitted.

If desired, the entire length of the induction pipe may be inclosed in the heating chamber, in which case the heat exchange portion of the induction tube may be correspondingly lengthened.

I claim:—

1. A vaporizer for internal combustion engines comprising a chamber adapted to surround the induction pipe, admission and outlet connections on said chamber for exhaust gases of combustion, a baffle device opposite said exhaust admission and spaced from the induction pipe, heat exchange devices on said induction pipe, a duct mounted within the induction pipe and having exhaust inlet and outlet connections, and cir- 130

- culating means adapted for moving exhaust gases through the said duct.
2. A vaporizer for internal combustion engines comprising a chamber adapted to surround the induction pipe, admission and outlet connections on said chamber for exhaust gases of combustion, heat exchange devices comprising webs on said induction pipe, a baffle mounted on said webs opposite said exhaust admission, said webs being thereby spaced from said pipe, a duct mounted within the induction pipe and having exhaust inlet and outlet connections, and circulating means adapted for moving exhaust gases through said duct.
3. A vaporizer for internal combustion engines comprising a chamber adapted to surround the induction pipe and having apertures in its end walls for the passage of said pipe, admission and outlet connections on said chamber for exhaust gases of combustion, a baffle device opposite said exhaust admission and spaced from said induction pipe, heat exchange devices on said induction pipe, a duct mounted in said induction pipe so as to traverse that portion of the said pipe which is surrounded by said chamber, a connection between the interior of said chamber and said duct, and a connection between said duct and circulating means adapted for moving exhaust gases through said duct.
4. A vaporizer for internal combustion engines comprising a chamber adapted to surround the induction pipe, admission and outlet connections on said chamber for exhaust gases of combustion, a baffle device opposite said exhaust admission and spaced from the induction pipe, heat exchange devices on said induction pipe, a duct mounted within the induction pipe, a connection between the interior of said chamber and
- said duct and a connection between said duct and the outlet from said chamber, and an ejector nozzle combination inserted in the latter connection.
5. A vaporizer for internal combustion engines, comprising a T-shaped pipe adapted for connection at its stem with a carbureted air supply and at the ends of its cross piece with engine induction pipes, a chamber inclosing said T-shaped pipe with the ends of the cross piece passing through apertures in the end walls of said chamber, admission and outlet connections on said chamber for exhaust gases of combustion, a baffle device opposite said exhaust admission and spaced from said T-shaped pipe, heat exchange devices on the cross piece of said T-shaped pipe, an ejector nozzle device connected with the outlet from said chamber, and a duct mounted within the cross piece of said T-shaped pipe and connected at one end with the interior of said chamber and at the opposite end with said nozzle device.
6. A vaporizer for an internal combustion engine comprising a chamber surrounding the induction pipe of the said engine, the said induction pipe, an inlet to the said chamber for the admission of hot exhaust gases of combustion, an outlet pipe for the exit of the said exhaust gases, a baffle device between the interior of the said chamber and the exterior of the said induction pipe for distributing the said exhaust gases over the surface of the said pipe, a duct mounted within the induction pipe, a connection from the said chamber to the said duct, a connection from the said duct to the said outlet pipe, means for the admission of hot gases to that part of the induction pipe surrounded by the said chamber and means for regulating the admission of such hot gases.

HERBERT KNIGHT.
